REDUCTION CRUSHER

Herbert Turner, Jr., Boscobel, Wis.

Application March 29, 1940, Serial No. 326,636

1 Claim. (Cl. 83—93)

This invention relates to rock crushing machines and has particular relation to a new and improved system of crushing and conveying rock aggregates for such machines.

It is among the objects of my invention to provide means for materially increasing the capacity of rock crushing machines and to provide means for accomplishing the crushing operation in a larger number of smaller steps without materially adding to the number of parts or increasing the size of such a machine.

Another object of my invention is to provide a rock crushing machine in which the reduction is accomplished in several stages and in which each stage is smaller than is the usual practice so as to increase the capacity of the machine and reduce the wear without material alteration of the machine.

Still another object of my invention is to provide a rock crushing machine giving a double reduction at the rolls without materially changing the structure of the machine.

Another object of my invention is to provide a new and improved roll type or secondary crusher.

Other and further features and objects of the invention will be more apparent to those skilled in the art upon a consideration of the accompanying drawings and following specification, wherein is disclosed a single exemplary embodiment of the invention, with the understanding, however, that such changes may be made therein as fall within the scope of the appended claim, without departing from the spirit of the invention.

In said drawings:

Figure 1 is a more or less diagrammatic outline, partly in elevation and partly in section, of a portable rock crushing plant constructed according to one embodiment of my invention.

Figure 2 is a plan view of the compound or dual roll crusher embodied in the device shown in Figure 1 with parts thereof broken away and shown in section, and

Figure 3 is a view in side elevation of the device shown in Figure 2, partly broken away to better show the structure.

Referring now more particularly to Figure 1, the device constructed according to one embodiment of my invention has a cranked main frame 10 supported on rear wheels 11 and front wheels 12. A primary or jaw crusher, such as illustrated at 13, in this embodiment of the invention is mounted on the low portion 10a of the frame 10. This crusher is provided with a hopper 14 for introducing the aggregate into the machine. The

movable jaw 15 of the crusher is driven by means of the crank and flywheel 17 and any suitable system of power which rotates the drive pulley 18, all in accordance with the usual practice.

The aggregate, after it passes through the primary crusher, drops onto the conveyor belt 19 and is conveyed upwardly toward the front of the machine and is discharged into the rotating wheel conveyor or elevator 21.

The elevating wheel 21 encircles the feeding conveyor 22, and material carried upwardly by the wheel elevator 21 is discharged onto the conveyor 22, the member 23 being a hopper and guide rails for guiding aggregate onto the conveyor 22. The aggregate is conveyed upwardly and discharged from the upper end of the conveyor 22 onto the vibrating screen 24. This screen is quite coarse and the coarsest material which will not pass through this screen travels downwardly over the screen and is discharged into the hopper 26 from which it drops down between the rolls of the secondary or double roll crusher illustrated generally at 27 and shown more particularly in Figures 2 and 3.

There are four rolls in the double roll crusher illustrated in Figures 2 and 3, and the material from the hopper 26 drops downwardly and passes between the primary rolls 28 and 29 of the double roll crusher 27. It is to be noted that these primary rolls are smaller in diameter than the rolls 31 and 32, and thus the spacing between the rolls is greater than is the spacing between the secondary rolls 31 and 32. The aggregate is crushed by the rolls 28 and 29 to a degree of fineness determined by the spacing of the rolls and then drops down onto the conveyor 19. The aggregate discharged from the primary rolls 28 and 29 passes upwardly along the conveyor 19, is discharged into the elevator wheel 21, and the wheel carries the material upwardly and discharges it onto the conveyor 22, which again discharges the material onto the screen 24.

The aggregate from the primary rolls 28 and 29 is now fine enough to pass through the screen 24, and drops down onto the fine screen 33. The material which will not pass through the screen 33 rolls downwardly across the screen and is discharged into the secondary hopper 34 which directs the aggregate down between the rolls 31 and 32. This aggregate is then crushed to a finer degree and drops downwardly onto the conveyor, and it is then conveyed back up by the conveyors 21 and 22 and discharged onto the screen 24. Of course this fine material will now

pass through both the screens 24 and 33, and will drop down into the hopper 36.

This hopper discharges onto the transversely extending belt 37 which carries the crushed aggregate out of the machine.

Of course some of the material from the jaw crusher 13 will be so fine that it will pass immediately through the screens 24 and 33 and into the hopper 36. The same is true with material passing through the primary rolls 28 and 29, and some of this material will pass immediately through both the screens 24 and 33 and be discharged.

It may, then, be readily understood that a large portion of the material discharged from the jaw crusher will immediately pass through the coarse screen 24, so that only a fractional part of the entire volume of aggregate is passed between the primary rolls 28 and 29. The same is true with the material discharged from the primary rolls 28 and 29, and a portion of this material will pass immediately through the screens 24 and 33 into the hopper 36 so that the secondary rolls need to work only on a still smaller portion of the entire volume of aggregate.

For instance, if half of the aggregate from the jaw crusher 13 has to pass through the rolls 28 and 29 and only half of the aggregate discharged from the rolls 28 and 29 has to pass through the rolls 31 and 32, the rolls 31 and 32 will have to operate only on about one-fourth of the entire volume of aggregate.

By using the dual or compound, double roll crusher and conveying system described, the process of reduction of the aggregate may be accomplished in three smaller steps as compared to the two large stages of the conventional machine. I have found that the capacity of a rock crushing plant is increased by as much as 50% by the use of my conveying system and dual or compound, double roll crusher. Furthermore, the machine may handle larger aggregate if desired, and the increased production of such a machine is accomplished with less wear and shock to the parts of the machine because the reduction at each stage is less drastic.

Referring now to Figures 2 and 3 in particular, in which the specific construction of the dual roll crusher is shown in detail:

A base or frame 40 may include a pair of longitudinally extending members 41 and 42 which may be in the form of structural I beams. These are adapted to be securely mounted on the upper surface of the main frame 10 of the crusher plant.

A plate-like guide member 43 is mounted on the top surface of each of these frame members 41 and 42. Similar plates or guide members 44 are supported at spaced distances above the bottom plate members 43 by means of spacer blocks 46 and 47 positioned above each end of each base member, and a pair of third spacer members 48 positioned intermediate the end spacer members.

Journal boxes 49 and 50 are positioned between the guide members 43 and 44 above each base member and adjacent the spacer members 46 at one end of the structure. The fixed roll shaft 52 is received for rotation in anti-friction bearings in these journal boxes. A labyrinth structure, indicated at 64, serves to protect the bearings from entry of grit and from the loss of grease.

One of the primary rolls and one of the secondary rolls 28 and 31 respectively are affixed to this fixed shaft by keys or the like (not shown).

The primary roll 28 has been broken away to better illustrate the structure. Each roll includes a central hub portion 53 having a radially extending flange as shown at 54 and at one end of the hub.

The outer or wearing surface of each roll is preferably made in the form of a hollow cylinder or drum-like member 55 having the inner surface thereof tapered outwardly toward the edges, as shown at 57 and 58.

The annular flanged portion 54 of the hub is, of course, provided with a similar taper so as to permit it to be snugly received within the tapered portion 57 of the outer wearing drum. An annular shaped web member 59 is adapted to be slidably received over the end 53 of the hub opposite the annular flange and, at the same time, to be wedged tightly into place within the tapered portion 58 of the outer drum.

I have found it desirable, when mounting a primary and a secondary roll on the same shaft, to place the hubs in position on this shaft so that the annular flanges are adjacent one another but spaced apart by means such as a washer 61. When this arrangement is used, the annular wedges 59 may be wedged into place and all the parts of both rolls may be rigidly mounted in their respective positions by means of a plurality of tie rods 62 long enough to extend through both rolls and threaded at their ends to receive clamping nuts 63.

The movable or companion rolls 29 and 32 to those heretofore described and shown at 23 and 31, are mounted upon another shaft 31, and this shaft is in turn mounted for rotation in journal boxes 82 and 83 which are substantially the same as that shown at 50.

These two journal boxes 82 and 83, however, are provided with guide members 84 along the lower and upper surfaces thereof to permit them to be slidably received between the lower and upper plate-like guide bars 43 and 44 respectively of the main frame.

The intermediate spacer members 48 are fixedly mounted between the guide bars 43 and 44 by means such as the bolts 86 and are also provided with openings 87 in which adjustable stop members 88 are received. These threaded stop members are adjusted on each side of the crusher device to fix the closest distance to which the movable rolls 29 and 32 may approach the fixed rolls 28 and 31. When the stop members 87 are properly adjusted, they are locked in position by means of the lock nuts 89.

In order to provide a certain amount of resilience in the crusher structure and to prevent breakage in case a piece of iron or the like is dropped into the crusher, the movable rolls are biased toward the stops by means of heavy springs 91. One of the springs is of course provided to act upon each end of the movable roll shaft 81. One end of one of the springs 91 is adapted to bear against the spacer member 47 and the opposite end of the spring to bear against a guide member 92 which is, in turn, slidably received between the guide bars 43 and 44. A guide rod 93 passing through an opening in the center of this guide member 92 and through the center of the spring is slidably received in an opening 94 passing through the spacer member 47.

This guide rod 93 is provided with threads to receive adjustment nuts 96. The end or head of a guide rod is of course intended to bear against each of the movable journal boxes 82 and 83 at all times, and it will be apparent that

threading the adjustment nuts 96 farther onto the adjustment or guide rods will serve to place the crusher springs 91 under greater compression to thus permit the pressure on the aggregate fed between the rolls to be increased or decreased as desired.

It is preferable that the main frame of the crusher structure be provided with cross members or spacers such as shown at 97. These cross frame members may be mounted as shown upon the ends of the main frame or, if desired, may be bolted or otherwise fastened to the lower surface of the I beams 41 and 42 comprising the lower part of the main frame.

The power counter-shaft 98 is mounted for rotation above one end of the main frame. A sprocket 101 fixedly mounted on this counter shaft serves, through the agency of a chain 102, to drive a sprocket 103 on the fixed roll shaft and another similar sprocket 104 affixed to the movable roll shaft.

Power can, of course, be transmitted to the movable roll by other means such as long tooth or "finger" gears.

A sheet metal cover or casing 106 is provided for totally enclosing the sprocket and chain driving mechanism.

Fly wheels may be mounted on each end of the counter shaft, as indicated generally at 99, to provide for smooth operation of the device. One of the fly wheels may act as a pulley through which power may be applied to the crusher.

Adjustment means, indicated generally at 107, are provided for adjusting the tension on the drive chain 102. The structure for securing this adjustment may include base members 108 fixedly mounted on the upper surface of the main frame work. These bases are provided with upwardly extending legs 109 in which adjustment rods 111 are threadedly received.

The power counter-shaft is, as stated before, supported for rotation in a pair of journal boxes 112 and 113, and these journal boxes comprise a part of or are mounted on top of slide rails 114. These slide rails are preferably mounted for sliding movement above their companion bases 108 and it will be apparent that they may be moved longitudinally of the bases, to take up any slack in the drive chain 102 as required, by means including the adjusting screws 111. Lock nuts 116 are provided to clamp the adjustment screws in position. It is obvious that any desired means may be used to secure the slide rails to the base members.

Although I have described a specific embodiment of my invention, it is apparent that modifications thereof may be made by those skilled

in the art. For example, one only of the two roll shafts may be power driven if desired, the other roll shaft and/or the rolls mounted thereon being permitted to rotate freely. To assist in feeding aggregate between the rolls of a device constructed in such a manner, the rolls may be fluted longitudinally.

It is obvious, also, that the large and small crusher rolls on each shaft may be made in a single unit, that is, each shaft may support a single unitary "stepped" roll rather than individual large and small rolls.

It may be desirable to deliver crushed rocks from the machine in graded sizes and, in such case, suitable conveying means may, of course, be arranged to remove the various sizes of rock after their passage through the several screens or between the compound rolls of the crusher.

Such modifications may of course be made without departing from the spirit and scope of my invention as set forth in the appended claim.

I claim as my invention:

In a portable rock crushing plant, a mobile base structure including side members, a primary jaw crusher disposed adjacent the forward end thereof, a screen having at least two superimposed decks disposed adjacent and substantially above the primary jaw crusher, a rotary wheel lift disposed at the end of the base opposite the primary jaw crusher, a lower conveyor having one end disposed below the jaw crusher for receiving material discharged therefrom, extending inwardly between the side members of the base and with the other end of the conveyor positioned to discharge into the rotary wheel lift, a second conveyor having its receiving end disposed within the rotary wheel lift directly above and at an angle to the lower conveyor and extending forwardly and upwardly to a position above the top deck of the screen, a roll crusher disposed above and discharging onto said lower conveyor, the roll crusher having pairs of primary and secondary rolls, the pairs of primary rolls being of smaller diameter than the secondary rolls, one roll of each pair of rolls being mounted on one of a pair of parallel crusher shafts, means for directing material, rejected by one deck of the screen, between the primary rolls of the roll crusher, means for directing material rejected by the other deck of the screen between the secondary rolls of the roll crusher, and discharge conveyor means extending transversely of the base between the jaw and roll crushers for receiving and discharging material passed through both decks of the screen.

HERBERT TURNER, JR.
